SPINDLE BRACKET

Eugene F. Monnia and Alex Marcus, Scranton, Pa., assignors of thirty-three and one-third per cent to Kenneth F. Mills, Scranton, Pa.

Application July 13, 1939, Serial No. 284,361

9 Claims. (Cl. 57—129)

This invention relates to spinning spindle brackets employed in the art of spinning cotton and silk.

In spinning machines of the above mentioned character, the spindles are subjected to severe duty and a maximum speed to produce a better grade and quality of yarn. This condition causes considerable wear on the spindles and the supporting bracket, which is accentuated usually by an unbalanced load imposed on the spindle or, if the latter should contain slight mechanical imperfections due to the fact that the load is located above the driving band an oscillatory or gyratory motion is set up around the normal center of gravity.

The above objections and disadvantages are overcome by providing a spindle bracket in accordance with this invention in which all shocks caused by high vibrations are absorbed and adjustments may be made to compensate for the wear on the bracket caused by the oscillatory and gyratory vibrations. Further, the spindle will be held yieldingly against the driving band in such a manner as to eliminate considerable vibration and allow the spindles to be driven at a much greater speed without liability of damage to the spinning machine and its associated parts.

Other objects and advantages of the invention will become apparent during the course of the following description taken in connection with the accompanying drawing wherein:

Figure 1 is a side elevational view of the spindle bracket embodying the invention.

Figure 2 is a top elevational view thereof showing the arc of the bracket with respect to the pivot bearing, and,

Figure 3 is a vertical cross sectional view taken on line 3—3 of Figure 2 looking in the direction of the arrows illustrating the bracket and pivot bearing in structural detail.

In the drawing, wherein for the purpose of illustrating the invention in detail and wherein like reference characters will be employed to designate like parts throughout the same, the reference character 5 will be employed to generally designate a spindle bracket including a vertical web portion 7 offset at the top and bottom as at 9 and 11.

The upper portion of the bracket web terminates in collar 13 having a central opening 15 for receiving an adjustable pivot pin 17, held in place by a set screw 19 and having its lowermost end pointed to form a bearing surface.

Formed on the lowermost portion of the bracket offset 11 is a bushing 21 surrounded by

an annular flange 23 and having its center provided with a bore 25. Mounted within the central bore 25 is a pivot pin 27 having its upper end pointed, as at 28, and said pivot pin 27 is held in axial alignment with the pivot pin 17 by means of a set screw 30.

The lowermost portion of the bushing 21 is externally threaded, as at 32, for being received in corresponding screw-threads formed in the rail of the spinning machine (not shown).

Swiveled between the axial aligned pivot pins 17 and 27 is a collar 34 having opposed bushings 36 and 38 preferably formed of a lubricant containing metal and each bushing is centrally formed with an opening 40 and 42, respectively, terminating at the inner end in a tapered portion for receiving the axial pointed pivot pins 17 and 27.

Extending laterally from the collar 34 is a bracket arm 44 having formed on the free end 20 thereof, a circular bolster support 46 having secured thereto a soft rubber washer 48 for resiliently supporting the spindle bolster. The spindle drive extends through the central opening 50 in the bolster support and through the shock absorbing washer 48 where it is connected to the spindle by the usual couple.

Also extending laterally from the collar 34 is a limit stop 52, the outer end of which engages the web portion 7 of the bracket to prevent oscillatory motion beyond a predetermined degree.

Pivotal or turning movement of the bracket 44 is yieldingly retarded by a coil spring 54 which encircles the collar 34 and has one end fixed to the web portion of the bracket 7, as at 56, and one end secured to the bracket arm 44 as at 58. Constant axial tension exerted by the coil spring 54 maintains the spindle drive in contact with the driving band of the spinning machine receiving apparatus.

In the event that the opposed bearings 36 and 38 become worn or pitted, the axial aligned pivot pins 17 and 27 can be moved toward each other to compensate for the wear on the pivot pins and bushings. This structure insures the swing bracket 44 against any lost motion and prevents vibration from end play.

It will be noted, that the bearing members are so positioned as to prevent chattering and binding and it is also to be noted that the form of the invention herewith shown and described is to be taken as a preferred embodiment of the same and that various changes in the shape, size and arrangement of parts may be resorted to with-

out departing from the spirit of invention or the scope of the subjoined claims.

What is claimed is:

- 5 1. A bracket for supporting spindles, comprising a bracket arm, opposed pivot bearings carried by the arm, and a spindle supporting member pivotally mounted between the pivot bearings.
- 10 2. A bracket for supporting spindles, comprising a bracket arm, opposed axially aligned bearings carried by the bracket arm, and a spindle supporting member pivotally mounted between the bearings.
- 15 3. A bracket for supporting spindle bolsters, comprising a bracket arm, opposed pivot bearings mounted in the bracket in axial alignment and a bolster supporting member pivotally mounted between the axial bearings.
- 20 4. A bracket for supporting spindle bolsters, comprising a bracket arm having opposed collars, pivot bearings mounted in the collars in axial alignment, a swinging bolster support mounted between the axial pivot bearings, and a shock reducing member carried by the bolster supporting member.
- 25 5. A bracket for supporting spindles, comprising a bracket arm having opposed collars, pivot bearings adjustably mounted in the collars, a swinging spindle supporting arm mounted between the pivot bearings and a shock reducing

washer mounted on the spindle supporting arm.

6. A spindle supporting bracket for spinning machines, comprising a bracket arm mounted on the rail of the spinning machine, a pair of axially aligned bearings carried by the bracket arm and a spindle supporting arm mounted between the aligned bearings. 5

7. A spindle supporting bracket for spinning machines, comprising a bracket arm adapted to be detachably secured to the spinning machine 10 rail, a spindle supporting arm journaled in the spindle supporting bracket, and shock reducing means carried by the spindle supporting arm.

8. A spindle bolster support for spinning machines, comprising a bracket arm adapted to be 15 detachably secured to the rail of the spinning machine, opposed axially aligned bearings mounted in the bracket arm and a spindle bolster supporting arm pivotally mounted between the opposed bearings. 20

9. A spindle bolster support for spinning machines, comprising a bracket arm adapted to be screw-threaded in the spinning machine rail, opposed axially aligned pivot pins carried by the bracket arm, a spindle bolster supporting arm 25 journaled between the pivot pin bearings and shock reducing means mounted on the spindle bolster supporting arm.
